[57] CLAIM

The ornamental design for a faucet spout, as shown and described.

DESCRIPTION

FIG. 1 is a front perspective view of a faucet spout showing our new design;

FIG. 2 is a rear perspective view thereof;

FIG. 3 is a top plan view thereof;

FIG. 4 is a front elevational view thereof;

FIG. 5 is a rear elevational view thereof;

FIG. 6 is a left side elevational view thereof, the right side being a mirror image;

FIG. 7 is a cross-sectional view, rotated 90 degrees taken along line 7—7 in FIG. 6;

FIG. 8 is a bottom plan view thereof;

FIG. 9 is a front perspective view of a second embodiment of faucet spout;

FIG. 10 is a top plan view of the faucet spout illustrated in FIG. 9;

FIG. 11 is a front elevational view of the faucet spout of the second embodiment;

FIG. 12 is a left side elevational view of the faucet spout illustrated in FIG. 9, the right side being a mirror image;

FIG. 13 is cross-sectional view, rotated 90 degrees taken along line 13—13 in FIG. 12; and,

FIG. 14 is a rear perspective view of the faucet spout illustrated in FIG. 9.

The broken line showing of the aerator in FIG. 1 is for purposes of illustration only and forms no part of the claimed design.
